LAVATORY

Jack N. Kaiser, Louisville, Ky., assignor to American
Radiator & Standard Sanitary Corporation, New York,
N.Y., a corporation of Delaware

Filed Apr. 2, 1962, Ser. No. 69,529

Term of patent 14 years

(Cl. D4—2)

Fig. 1.

Fig. 2.

Fig. 3.

FIGURE 1 is a front perspective view of a lavatory embodying my new design.

FIGURE 2 is a side elevational view thereof.

FIGURE 3 is a front elevational view thereof.

Both sides of the lavatory are substantially of the same appearance.

I claim:

The ornamental design for lavatory, substantially as shown and described.
